OTHER PUBLICATIONS

Notice of Allowance dated Apr. 18, 2016 from U.S. Appl. No. 29/527,085.

Office Action dated Feb. 1, 2016 from U.S. Appl. No. 29/516,707.

Primary Examiner — Wan Laymon*Assistant Examiner* — Clint A Samuel(74) *Attorney, Agent, or Firm* — Ward and Smith, P.A.;
Ryan K. Simmons(57) **CLAIM**

The ornamental design for a closeable container, as shown and described.

DESCRIPTION

FIG. 1 is a perspective view of a closeable container showing a new design;

FIG. 2 is a top plan view thereof;

FIG. 3 is a front elevation view thereof, the rear being a mirror image;

FIG. 4 is a left side elevation view thereof, the right side being a mirror image; and,

FIG. 5 is another perspective view showing the closeable container of FIG. 1 in an open configuration.

In the Figures, the dash-dot broken lines are for the purpose of illustrating perforations.
